The ornamental design for a handle and inner compartment portion of a handbag, as shown and described.

DESCRIPTION

FIG. 1 is a side elevational view of a handle and inner compartment portion of a handbag showing my new design;

FIG. 2 is an end elevational view thereof as seen from the right of its FIG. 1 position;

FIG. 3 is a top plan view thereof;

FIG. 4 is a bottom plan view thereof;

FIG. 5 is an end elevational view thereof, showing the end opposite to that shown in FIG. 2; and,

FIG. 6 is a side elevational view thereof, showing the side opposite to that shown in FIG. 1.
